ALEXANDER C. TWINING, OF NEW HAVEN, CONNECTICUT.

Letters Patent No. 90,137, dated May 18, 1869.

IMPROVEMENT IN DETACHABLE FIXTURE FOR CASTERS.

The Schedule referred to in these Letters Patent and making part of the same.

Be it known that I, ALEXANDER C. TWINING, of the city and county of New Haven, and State of Connecticut, have invented a new and improved Detachable Fixture, being a mode of readily attaching and detaching a shaft or pintle to and from a socket or plate, and applicable especially to casters; and I hereby declare that the following is an accurate and full description of my said improvement, reference being had to the accompanying drawing.

In the drawing, the three middle figures, marked respectively "elevation," "face," and "end view," and connected by lines of reference up and down with each other, are primarily referred to.

The figures on the left hand and on the right merely exhibit variations and equivalents.

Let $b b b$ be a plate or socket, into whose bore the shaft or pintle $p p$ is to be fixed, but yet to be easily detachable.

Let the socket spread at one extremity, as shown by the rim or collar $c c c$, and let a slot, $m k k z$, be sunk in its face crosswise of the bore, (see "face,") to receive an elastic wire or strip, $m z$, (see "strip,") lying in it, and bent around to clasp $c c$ both right and left. This will hold the strip or wire, and form a spring of two branches of force sufficient to hold $p p$ in the bore, as will appear.

The spring is concave, as at n , in both branches to let the shaft be pressed through and into the socket, by spreading apart the branches.

For this purpose, supposing the shaft when attached to have a shoulder, $j j$, beneath the spring, it must have a swell or enlarged ring running around it above the spring, as s .

Now, if s were a shoulder, the shaft would not come out, unless $m z$ were forcibly parted the entire width of s ; but if s is a swell simply, as in the drawing, it can be withdrawn by a sufficient pull and twist. The degree of force for the pull will be regulated by the force of $m z$, and the sharpness or suddenness of the swell.

It is a valuable property of $m z$ that in consequence of its length of wire it may spread liberally, even although the wire's cross-section is large enough for a comparatively strong spring. But to prevent its closing upon $p p$, and thus producing friction that would obstruct the shaft's turning, the small knobs $k k$ are left in the slot $m k k z$, to keep the branches apart, thus leaving only the balance of the spread to be made by s when pushed in, as before described.

But k may be dispensed with, if the straight segments of the spring are in contact and receive each

other's tension, so as to keep one another mutually apart.

The figures on the right show $m n z$ and k attached, not in a slot, but outside the face $c c$ of a ridged socket, called a "ridge-bed" in my patent therefor. The corresponding figures on the left have $m n z$ fastened at the upper extremity of $b b b$, or in some other portion of its extent, as the figures sufficiently show. If instead of k the bend m of the "strip" should be sharpened, n and n would approach, and might even lap past one another. If, in addition, z is permanently bent to an open form, it is obvious that when $m n z$ is fastened in place on $c c$, the launches of the curves x and y will press and restrain one another to such an extent that $p p$ may pass between without resistance or friction, whether into $b b$ or out of it, except as the swell or enlargement s shall offer resistance. This last-described and peculiar structure of the spring $m n z$, instead of k , I do not claim at present, but reserve the claim for a patent to be applied for hereafter.

The merit and novelty of the combination herein described for obtaining a measured resistance to the withdrawal of $p p$ from $b b b$ are owing chiefly to the attachment of $m n z$ to $b b$ in a manner to traverse the bore of the latter, near its circumference, by a twofold spring inclosing, or capable of inclosing, $p p$. Certain other particulars are, however, of no slight importance. Such is the knob k , or its tantamount formation by the spring itself; such also is the swell or enlargement s , instead of a channel in $p p$, which tends to weaken the latter. But the two branches of $m n z$ may be separate strips or wires, and they may be formed straight, or sloping regularly from the bore to the extremity of the rim, or of yet other forms, and they may be attached by inserting their ends into holes in $c c$ or $b b$, or in any other known way; or one branch by itself may serve in certain cases.

What I claim, and desire to secure by Letters Patent, is the following:

1. I claim the combination of a plate or socket with the elastic strip, wire, or branches traversing or skirting the bore, and attached, substantially as and for the purpose set forth.

2. Also, the knob k in the same combination.

3. Also, the swell s of the shaft or pintle in the same combination.

ALEXR. C. TWINING.
